(57) **CLAIM**

The ornamental design for a pocket with breathing apparatus, as shown and described.

DESCRIPTION

FIG. 1 is a perspective view of a pocket with breathing apparatus showing my design;

FIG. 2 is a front view of FIG. 1;

FIG. 3 is a back view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a perspective view of a second embodiment of a pocket with breathing apparatus showing my new design;

FIG. 9 is a front view of FIG. 8;

FIG. 10 is a back view of FIG. 8;

FIG. 11 is right side view of FIG. 8;

FIG. 12 is a left side view of FIG. 8;

FIG. 13 is a top view of FIG. 8; and,

FIG. 14 is a bottom view of FIG. 8.

The thick broken lines shown in FIGS. 1-3, 6, 8, 9, 10 and 13 represent stitching. The thin broken lines shown in FIGS. 1-6, and 8 are for illustrative purposes only and form no part of the claimed design;
